INVENTOR

HENRY T. BUSSMANN,

By Very M. E. E. Attorney

Patented Aug. 4, 1925.

UNITED STATES PATENT OFFICE.

HENRY T. BUSSMANN, OF ST. LOUIS, MISSOURI.

ELECTRIC FUSE.

Application filed May 7, 1919. Serial No. 295,367.

To all whom it may concern:

Be it known that I, HENRY T. BUSSMANN, a citizen of the United States, residing in the city of St. Louis, in the State of Missouri, have invented a certain new and useful Electric Fuse, of which the following is a clear, full, and exact description, such as will enable others skilled in the art to make and use the same.

10 My invention relates to electric fuses and refers particularly to that type of fuse known as the refillable cartridge fuse; yet I do not limit my invention to this type as certain of my improvements are likewise desirable in other types of fuses.

15 Fiber, which is principally used as a casting for electric fuses, will not hold its threads when used very often. It will shrink, allowing the fittings attached thereto to become loose and permit the escape of gas and flame on the blowing of the fuse. It will, when subjected to dampness, swell to such an extent as to make removal of the fittings difficult or impossible. I have overcome these difficulties in a manner that causes 20 the fuse to be more tightly enclosed when the fiber shrinks, and still not affected when the fiber swells.

25 Difficulty has been experienced in refillable knife blade fuses by reason of the contact blades or terminals not being positively aligned with each other. When this occurs, the jaws of the fuse block are sprung or bent out of shape, resulting in poor contact, and 30 consequent premature burn-out of the fuse link. I have overcome this trouble in a manner that is absolutely positive; yet so simple that those inexperienced in the art cannot in renewing the fuse cause the blades 35 to be out of alignment; even to a slight degree.

I have also eliminated the difficulties experienced by sidewise movement of the terminals, and have provided means for substantially preventing edgewise movement of the terminals caused by inserting the fuse into the jaws of a fuse block. This edgewise movement results in injury to the fuse link or loosening of its fastenings, resulting in poor contact and consequent premature burnout of the fuse link.

Another object of my invention is to overcome the difficulty that has been experienced in assembling and fastening the fuse link to the terminals in a straight line. The difficulty has been that when the bolt intended

for this purpose is pulled up tight, it invariably pulls the terminals out of line with the link, making it impossible to assemble the fuse. Attempts to bring the terminals in line with the link after being assembled result in injury to the fuse link or loosening of its fastenings.

A great deal of trouble is also experienced in the assembling of a refillable fuse by reason of the fact that in assembling the fusible element, i. e., the terminals and the fuse link, a variation in length occurs; due to the clearance necessary in the bolt holes in the terminals and fuse link. When the fusible element is assembled short, the fuse cannot be put together at all and must be re-assembled; when the fusible element is assembled long, the link must be crushed or bent to allow the case to be closed. I have overcome this difficulty in a simple manner, by providing means for taking care of these variations.

These and other advantages of my invention will be more readily understood by reference to the accompanying drawings, which show a preferred embodiment of my invention. In describing the device shown in the drawings hereto attached and described in the specifications, I do not limit my invention to the precise form, shape or construction of the fuse shown, or to the several parts thereof, as various alterations can be made without changing the scope of my invention.

Fig. 1 is a view of my fuse, having a section broken out to show the arrangement thereof. Fig. 2 is a view of the fuse ninety degrees from the position shown in Fig. 1. Fig. 3 is a view of a closing washer. Fig. 4 shows a terminal holding washer. Fig. 5 is an inside view of the end ring. 6 is a view of the end of the fuse. 7 is a modification of the ring shown in Fig. 5. 8 is a cross-sectional view on the line 8-8 of Fig. 1. Fig. 9 shows a view of my fuse having a section broken out to show a modified arrangement thereof. Fig. 10 is a perspective view of another modified form. Fig. 11 shows a cross-sectional view of the copper terminal with modified link holding lugs.

In the drawings, 9 is a casing which is made of hard fiber or other suitable material. 10 is a member, preferably of metal, and preferably in the shape of a ring, which member is fitted partly within the casing and held by threads 11. 12 is a rivet pre-

venting relative rotational movement between the casing 9 and the member 10. 13 is a shoulder on the member 10. 14 is the cap engaging portion, the threads thereon 5 engaging with the threads of the cap 15. From this it can be readily seen that by reason of the member being fastened inside the casing, the shrinking of the fiber now serves to hold the casing more firmly to the 10 element. The cap engaging portion being metal, the swelling of the fiber does not prevent removal of the cap; the shrinking of the fiber does not permit the cap to become loose; the threads used when removing 15 or replacing the cap are on the metal portion instead of the fiber and will not readily wear or chip. The cap may be attached by other means, but preferably by threads, as shown.

20 It will be readily understood that this member 10 may be of different forms and may be held to the casing by other means and that the shoulder 13 may be dispensed with, as, for example, by using a cap that 25 does not overlap the fiber as shown in Fig. 9, but I prefer this form as it admits of the production of a more attractive and conveniently assembled fuse.

16 is a flat blade terminal which extends 30 within the member 10. The inner periphery of this member is so shaped that the terminal is prevented from rotational movement. While any non-circular interior will so hold the terminal, for instance, a diagonal opening, as shown at 26 in Fig. 7, I have found it preferable to use two 35 grooves for that purpose, as shown at 17 in Fig. 5.

One of these members with grooves or 40 other non-circular interior is placed on each end of the casing, with the grooves properly positioned, so that the terminals are held in the same plane and in substantial alignment with each other.

45 These grooves or other form of non-circular interior extend preferably through the entire length of this member. They are of such a dimension as will closely fit the terminal and yet permit the ready removal 50 and insertion thereof. They are preferably shaped to conform to the edge of the terminal. As a result of this, they act as a seat for the terminal, and by reason of their length, effectively prevent any sidewise 55 movement of the terminal, that would cause a strain on the fuse link; which, being of soft metal and comparatively small cross-section, would be easily injured by such sidewise strain.

60 On the interior of the member I provide bearing points having a spaced relation to each other, between which points the terminal is positioned with only a limited clearance. When the terminal is subjected 65 to edgewise movement, as, for instance,

when a fuse is inserted in the fuse block, the terminal will bear on the points 27, 27' or 28, 28', and by reason of the separation of these points and the small clearance allowed, only a very limited movement 70 of the terminal is permitted. The member must be made of a material of practically unchanging dimension, so as to maintain these dimensions constant. Fiber, as now made, cannot be used for this purpose, as 75 the shrinking or swelling of the fiber would not maintain this constant clearance and would cause the terminals to bind. I may make this member with an opening considerably larger than the width of the terminal and provide projections or bearing points at the outside and inside ends thereof as shown in Fig. 9 where the terminal is positioned, but the effect would be the same, as the terminal will touch at points 80 27, 27' or 28, 28', as shown.

While I have accomplished this result by the use of the grooves shown, it is readily apparent that where other means are used for preventing rotational or sidewise movement, that I may dispense with the use of grooves, as the substantial prevention of edgewise movement I accomplish by means of the constant relation of bearing points separated from each other.

It will also be understood that the means of holding the terminals against rotational movement, against sidewise movement, against edgewise movement, and in alignment with each other, may be used on other 90 forms of fittings within or without the casing and that while grooves of substantial length are my preferred form of construction for the prevention of edgewise and sidewise strain, it can be readily understood by those 100 acquainted with the art, that many variations of this arrangement are possible without varying from the spirit and nature of my invention.

In the above I have described a structure, 110 comprising a casing and members at each end, but I may make this a unitary structure of insulating material of unchanging dimensions as shown in Fig. 10.

The terminals 16 are connected to the fuse 115 link 21 by bolts 22 or other suitable means extending through openings 23 in the link and terminal. Upon the terminal 16 are lugs 24 so spaced as to allow a fuse link to be 120 placed in position between them, but substantially preventing any sidewise movement. By reason of the relation of the lugs 24 to the opening 23, the fuse link 21 is held in alignment with the terminals, and cannot be pulled out of such alignment when fastening the bolts. These lugs are preferably 125 made by stamping the terminal, and instead of being struck up at right angles to the terminals, they may be made to incline towards each other in such wise that only a 130

fuse link of a predetermined thickness or less, may be inserted within the lugs as shown in Fig. 11.

The terminal holding device 19 may be of any desired form, although I prefer the notched washer shown, as it is especially advantageous in connection with the grooves in the member or ring 10, as they serve to close the space left open by that portion of the notch in the washer not engaging the terminal, thereby completely closing the case. This is particularly advantageous as it prevents the deposit of metal on the threads of the cap or on the packing washer 18. This washer may be of any easily compressible non-insulating or insulating material.

It is necessary that some clearance be allowed in the holes in the terminals and fuse link for the bolt which fastens them together. This causes a variation in the length of the fusible element when they are assembled. There is also a variation in the length of the structure which consists of the casing and closures, which closure might consist of a cap alone, or a cap and washers. The result is that heretofore the fuse link frequently has been injured in an effort to lengthen or shorten the fusible element referred to, so as to adapt this structure to the casing and closures. I have provided an arrangement in connection with the structure comprising the terminals and fuse link, so that despite variations in the length of this structure, or in the length of the structure comprising casing and closures, the fuse may be easily and quickly assembled without injury to any part thereof. In the arrangement shown in Fig. 1, I have made the space 25 in the terminal 16 of greater width than the thickness of the terminal holding washer 19 shown in Fig. 4, that fits within such space. This holds the terminal against longitudinal movement, except to the extent of the difference between the thickness of the washer and the width of the slot, which is sufficient to compensate for the variances above mentioned. This structure comprising terminals and strip I have designated as the "floating element" when arranged as above suggested, because this member during assemblage moves or floats to admit of adjustment with the length of casing and closures, and is to be regarded as broadly covering any arrangement by which the variations mentioned are compensated for, inasmuch as I do not limit myself to the "floating element" herein shown and described, as other and equivalent forms thereon may be employed without departing from the scope of my invention.

I claim as my invention:

1. In a renewable fuse of the unfilled type, a fibre casing, a closure, a member with an exterior periphery threaded substantially throughout its length, which member is

partly threaded within the casing, a knife blade terminal extending within the member and through the closure, and means on the closure for engaging the threaded portion of the member outside the casing. 70

2. In a fuse, a casing, a cap, a cap holding member detachably engaged by the cap, said member having grooves in the inner periphery thereof, and a flat blade terminal positioned within the grooves of the member. 75

3. In a fuse, a casing, a cap, a fuse element comprising flat blade terminals, fuse link and connection means therefor, a cap holding member detachably engaged by the cap and having its interior so shaped that the fuse element may be passed therethrough and yet positioned therein against rotational movement. 80

4. In a renewable knife blade cartridge fuse, the combination of a casing, a threaded cap, a metallic cap holding member threaded within the ends of the casing and extending beyond the casing, threads on a portion of the cap holding member beyond the casing, said member having oppositely spaced recesses at the outer end thereof adapted to engage a part of the terminal and limit the rotational movement of the terminal. 85

5. In a refillable fuse, a tubular casing, a closure, a flat blade terminal arranged to pass through the casing, a member distinct from the closure permanently attached to the casing, and of practically unchanging dimensions adapted to extend about the terminal, said member having on its inner periphery substantially separated points on each of opposite sides thereof, said points having a constant spaced relation to each other and acting as bearing points between which points the terminal, having a certain limited clearance, is removably positioned, whereby the edgewise movement of the terminal relative to the casing is substantially prevented. 100

6. In a refillable fuse, a flat blade terminal, a casing and means beyond the end of the casing coacting with means on the terminal for allowing the terminal a certain limited longitudinal movement relative to the casing. 115

7. In a refillable fuse, a flat blade terminal, a threaded cap and means held by the cap coacting with means on the terminal for allowing the terminal a certain limited longitudinal movement relative to the casing. 120

8. In a refillable fuse, a flat blade terminal, a casing, a cap, a terminal holding device adapted to be pressed by the cap and means on the terminal coacting with said device for allowing the terminal a certain limited longitudinal movement relative to the casing. 125

9. In a refillable fuse, a casing, a flat 120

blade terminal, a terminal holding device, a cap adapted to be put on and removed independently of the terminal holding device and means on the terminal coacting with said device for allowing the terminal a certain limited longitudinal movement relative to the casing.

10. In combination with a structure comprising a casing and closing structures therefor, a structure comprising terminals and a fuse link, one of said structures having means beyond the end of the casing coacting with means on the other structure for compensating variations between the lengths of the two structures.

11. In a refillable fuse, a casing, a closure, a flat blade terminal adapted to be passed through the casing, a member connecting casing and closure and having with- 20 it means of practically constant spaced relation for positioning the terminal against rotational movement.

12. In a renewable fuse of the unfilled type, a fibre casing, a cap, a metallic member externally threaded within an end of the casing and having an externally threaded portion beyond the casing, a terminal extending within the member and through the cap, means between the metallic member 25 and the cap adapted to hold the terminal against longitudinal movement relative to the casing, and means on the cap for engaging the threaded portion of the member outside the casing.

13. In a refillable fuse, a casing, a flat blade terminal arranged to pass through the casing, a cap, a cap holding member permanently attached to the casing having substantially separated points of constant spaced relation to each other on each of the opposite parts of the inner periphery of said member, between which points the terminal, having a certain limited clearance, is removably positioned, whereby the edge- 45 wise movement of the terminal relative to the casing, is substantially prevented.

14. In a refillable fuse, a casing, a cap holding member attached to the casing, a fuse element comprising a flat blade terminal and a fuse link connected thereto, which are adapted to be passed through the member and means on the inside of the member for substantially holding the terminal against sidewise movement.

15. In a refillable fuse, a casing, a cap holding member attached to the casing, a fuse element comprising a flat blade terminal and a fuse link attached thereto, which are adapted to be passed through the member, and means within the member of practically constant spaced relation for substantially preventing the axial and edgewise movement of the terminal.

16. In a refillable fuse, a casing, a cap, a

metallic cap holding member attached to the casing, a flat blade terminal having its edges fitting within and closely bordered by faces of said member and a terminal holding device adapted to hold the terminal against longitudinal movement; fitting about the terminal and coacting with the member to close the end of the fuse.

17. In a refillable fuse, a casing, a cap, a flat blade terminal, a cap holding member attached to the casing, and having a portion thereof extending beyond the end of the casing, removably connected with the cap, and having oppositely disposed devices within which the terminal is removably positioned with a certain limited clearance whereby edgewise and sidewise movement of the terminal is substantially prevented.

18. In a refillable fuse, a casing, a cap, a flat blade terminal, a cap holding member permanently attached to the casing and detachably engaged by the cap, said member having oppositely disposed devices in constant spaced relation with each other, within which the terminal is removably positioned, whereby rotational and edgewise movement is substantially prevented.

19. In a renewable knife blade cartridge fuse, a casing, a metallic member threaded within the end of the casing and having an externally threaded portion extending beyond the casing, a transversely movable terminal holding device outside the end of the metallic member, a knife blade terminal extending within the metallic member and having means for engagement with the terminal holding device and a closure element threaded on a portion of the metallic member beyond the casing.

20. In a renewable knife blade cartridge fuse, a casing, a metallic cap holding member threaded into the casing and having a portion extending therefrom, a terminal, having a recess at its edge, extending within the cap holding member, a transversely movable terminal holding means beyond the end of the cap holding member and embracing the flat sides and a recess in the terminal, a slotted washer removably fitted around the terminal of a size greater than the aperture in the cap holding member, and a cap adapted to be threaded on the cap holding member and compress the washer against the terminal holding means.

21. In a knife blade renewable fuse of the unfilled type, a fibre casing, a metallic member having external threads engaging threads within the end of the casing and having an externally threaded shouldered portion outside the casing, a knife blade terminal adapted to extend within said member and a closure element screwed on the externally threaded shouldered portion of said member.

22. In a refillable fuse, the combination of a fuse element comprising terminals and fuse link and an enclosing structure having ends whose outer periphery is arranged to 5 removably hold a cap and whose inner periphery is so shaped that the fuse element may be positioned therein against rotational movement.
23. In a renewable knife blade fuse of the 10 unfilled type, a fibre casing having threads on its interior at an end thereof, a knife blade terminal, a closure means of substantially unchanging dimension, adapted to substantially close the end of the casing, except for an opening through which the removable knife blade terminal closely fits and extends outwardly, and means on the knife blade terminal coacting with the closure means for limiting the longitudinal movement of the terminal; said closure 15 means having threads on its exterior periphery engaging the threads in the fibre casing, whereby the shrinking of the fibre contributes to increase the engagement of the threads of the casing with the threads 20 of the closure means.
24. In a renewable knife blade fuse of the unfilled type, a fibre casing having threads 25 on its interior at an end thereof, a knife blade terminal, a closure means of substantially unchanging dimension, adapted to substantially close the end of the casing, except for an opening through which the removable knife blade terminal closely fits and extends outwardly, and means on the knife blade terminal coacting with the closure means for limiting the longitudinal movement of the terminal; said closure 30 means having threads on its exterior periphery engaging the threads in the fibre casing, whereby the shrinking of the fibre contributes to increase the engagement of the threads of the casing with the threads 35 of the closure means.

HENRY T. BUSSMANN.
